UNITED STATES PATENT OFFICE.

HAROLD A. COTTLER, OF BROOKLYN, NEW YORK.

CROWN-MOUNTED PORCELAIN-FACING ELEMENT.

Application filed September 26, 1924. Serial No. 739,978.

To all whom it may concern:

Be it known that I, HAROLD A. COTTLER, a citizen of the United States, and a resident of the borough of Brooklyn, county of 5 Kings, city and State of New York, have invented certain new and useful Improvements in Crown-Mounted Porcelain-Facing Elements, set forth in the following specification.

10 This invention relates to artificial teeth. Its object is to make possible the crowning of a natural tooth with a minimum amount of preparation of the natural tooth permitting the use of a completely enclosing 15 metal crown and, at the same time, providing for a labial facing of enamel-like material simulating the appearance of a natural tooth.

More specifically, it is an object of the 20 invention, in addition to the general object recited, to improve the means and method of fitting the facing to the crown, adjusting and adapting it to the gum line and gum contour firmly anchoring it to the crown 25 and, at the same time, minimizing, if not substantially eliminating, all visibility of the metal portion of said crown.

Heretofore, combined metal crowns and 30 facings have been fabricated in such a way that the facing constituted a panel made accurately to fit within a completely enveloping flange extending around all four sides of the panel and adapted to be burnished over to hold the panel in place.

35 More particularly, it is the object of my invention to overcome the disadvantages requiring the facing to be shaped to fit into a virtual socket embracing all its four edges. An object also is to provide for lengthwise 40 adjustment of the facing without tedious and expensive alteration of the facing itself and without any alteration of the metal crown.

Still further objects of the invention are 45 to improve the detail construction of a metal tooth crown and the adaptation thereto of a labial finished facing, all of which objects will better be understood by reference to the illustrative embodiment of my invention 50 described in the following specification and shown in the accompanying drawings which form a part of my specification. It is to this illustrative embodiment that my claims are directed merely for purposes of 55 illustration and not limitation.

In the drawings, Figure 1 is a diagram-

matic labial view with the gum line and root indicated in dot and dash lines with the preferred finished construction embodying my invention; 60

Fig. 2 is a similar view with the finished facing removed, but with its edge shown in dot and dash lines;

Fig. 3 is a labial vertical cross section;

Fig. 4 is a horizontal cross section through 65 the plane of line IV—IV of Figure 3; and

Fig. 5 is a perspective view of the crown ready for the insertion and mounting of the facing, but with the facing omitted.

A metal crown A is fabricated according 70 to any approved method to fit about and conform to the size and contour of the natural tooth to be crowned, the preparation of the natural tooth, of course, providing for the proper positioning of the biting edge 75 and being cut away somewhat along the labial face to permit of the application of a finishing facing B, which is to simulate in appearance the labial exposed surface of the patient's natural tooth. Essentially to 80 my invention, the metal crown A must provide a pair of opposing laterally spaced undercut flanges 1 and 2, facing towards each other and providing therebetween a virtual keyway 3 for the reception of the facing B 85 which functions therein substantially as a key. It is necessary that the metal structure of the crown A be sufficiently rigid and strong to withstand the outward stresses upon the flanges 1 and 2 occasioned by the 90 forcible contact therewith of the facing B. This is best accomplished by casting the crown A from the usual gold alloy, but casting it as an entirety with the flanges and all of its other integral parts of the structure. This is readily accomplished by 95 processes known in the art after first forming a suitable model in wax. Although I have shown the keyway overlying one wall 100 4 forming an integral part of the tooth crown A and functioning in the structure illustrated as a tension member, tending to resist separation of the flanges 1 and 2, it is not essential to my invention that the metal crown structure actually extend across 105 from flange to flange. It may be perforated or omitted. But in the preferred embodiment of my invention, the cross wall 4 is present. Preferably, the undercut flanges 1 and 2 taper towards each other away from 110 the incisal edge 5 of the structure and, in any event, I prefer that they be straight.

The keyway 3, as is illustrated, is open at both ends before the application of the facing B. That is, it is open for the free insertion of the facing B at the incisal end 5 and is free and unobstructed at the gum end 6.

I prefer that the facing B be formed initially somewhat longer than the surgeon actually contemplates for its finished length 10 and that it be provided along its side edges with bevels 7 and 8 complementary to the undercutting of the flanges 1 and 2, and, of course, parallel therewith. The crown A is properly mounted upon the prepared natural tooth and cemented in place. The partially prepared facing B may then be forced down through the incisal edge of the crown between the flanges 1 and 2 so that its bottom end or edge 9 may be studied with relation to the gum contour and so that its entire appearance relatively to the other tooth may be studied. It may then readily be slipped out and altered in its configuration to conform to the ideas of the surgeon. Again, 25 it is slipped into the keyway. One great advantage of my invention is that this facing B may, during the course of its fabrication, be tested again and again in the actual position in which it is to be worn. Of course, it is preferable, before this personal fitting takes place that its under face 10 be shaped concavely to fit the convex wall 4, whether this wall 4 be the metal wall 4 or the face of 30 the patient's natural tooth. After the size and configuration of the facing B has been determined, completely, its incisal edge 11 should be finished off and this facing is then permanently seated in the keyway 5 with a 35 suitable cementitious material applied both to the wall 4 and to the rear face 10 of the facing B. A film or layer 12 of such cement between the wall 4 and the facing B serves to aid in holding the facing mounted on the crown, but in accordance with my invention, 40 the mounting of this facing is not dependent alone upon the cement. I preferably provide an outstanding edge or lip 13 along the incisal edge 5 of the metal crown, which, during the fitting of the facing, clears the 45 keyway 3 to leave the same unobstructed for the entrance of the facing, but after the facing has been finished and permanently inserted, I burnish or swage this lip 13 over the incisal edge of the cementitious layer 12 as indicated in Figure 3, which protects the 50 facing B at the locality of greatest wear and prevents the forcing into the crack between the facing and the crown of foreign matter. 55 In addition to this, however, in the preferred embodiment of my invention, the tapered positioning of the flanges positively

locks the facing against movement responsive to incisal pressure. In other words, the position of these flanges is such as to exert a 65 component of re-active force in opposition to all force coming from an incisal direction.

It is preferred that the positioning of the flanges 1 and 2 correspond as nearly as possible with the lateral profile limits of the crown B and it has been found in the actual shaping of the facing B that it may slightly bulge so that a front view of the tooth virtually shows no metal as indicated in Figure 75 1. It is also to be noted that the unrestricted opening at the gum end of the keyway readily permits the positioning of the facing B so that it may extend and actually be fitted into a position below the gum line, although, of course, this positioning is not essential to my invention and it is not a necessity that the facing be actually forced below the gum line. According to one good 80 practice the facing at its gum edge is shaped accurately to fit the gum contour without penetration but with such close contact as to give the appearance of a natural tooth.

The inventive thought may have a variety of expressions, as is contemplated by what I claim and desire to secure by United States Letters Patent as follows:

1. In artificial teeth, a metal crown adapted closely to embrace and enclose a prepared natural tooth, the labial portion of said crown being formed with opposed laterally spaced undercut flanges faced towards each other approximately along the lengthwise profile edges of said crown and forming on said crown a virtual keyway open at both ends, in combination with a tooth facing keying between said flanges in said keyway and free at its gum end to be adjusted relatively to said crown and the gum line.

2. The structure described in claim 1 and further characterized by the fact that said opposed flanges are positioned so that they taper towards each other away from the incisal end of the crown so that the anchorage of said facing by said flanges exerts a 105 re-acting component of force against incisal forces.

3. The structure as described in claim 1 and further characterized by the fact that a protective lip is provided along the incisal entrance into said keyway which is capable of being burnished over as a protective covering for the parting space between said crown and the incisal edge of said facing.

In witness whereof, I have signed my name to this specification this 14th day of August, 1924.

HAROLD A. COTTLER.
